UNITED STATES PATENT OFFICE.

CHARLES SPAETH, OF CLEVELAND, OHIO, ASSIGNOR TO THE MARVEL EQUIPMENT COMPANY, OF CLEVELAND, OHIO, A CORPORATION OF OHIO.

LIQUID-DISPENSING APPLIANCE.

Application filed April 23, 1924. Serial No. 708,339.

To all whom it may concern:

Be it known that I, CHARLES SPAETH, a citizen of the United States, residing at Cleveland, in the county of Cuyahoga and State of Ohio, have invented certain new and useful Improvements in a Liquid-Dispensing Appliance, of which the following is a specification.

My invention relates to an improvement in liquid dispensing appliances, and in general my object is to provide a simple and efficient drip catcher and return drain pipe for a dispensing pump and tank the pipe being rotatably seated within the base of the pump and held under spring tension in sealing position therein by a spring and collar. As arranged, the collar is a separate part sleeved upon the pipe and adapted to be set to compress and contract the spring, whereby a constant end thrust and torsional force may be applied to the base end of the drain pipe.

In the accompanying drawing, Fig. 1 is a perspective view of the upper end of a dispensing tank embodying a pump and my improved drip catcher and drain pipe. Fig. 2 is an enlarged sectional view of the base of the pump, and a side view of the drip catcher and drain pipe bodily removed therefrom. Fig. 3 is a sectional view of the base of the pump and the drain pipe seated therein in drip catching relation to the discharge spout of the pump. Fig. 4 is a horizontal section on line 4-4 of Fig. 3, showing the stop on the drain pipe engaged with the outlet nipple of the spout.

The present invention is especially applicable to oil dispensing pumps which are mounted upon or associated with a tank or receptacle containing the oil or other liquid to be dispensed, and from which a measured amount of oil is discharged into a receiving vessel placed beneath an overhanging discharge spout for the pump. As exemplified herein, the pump P comprises a base 2 seated upon top 3 of a tank T, and an intake pipe 4 connects with an intake passage 5 within base 2, the pipe extending downwardly into the liquid within the tank. Pump P may be constructed in various ways, but a common type of lift pump used for this purpose embodies a valved piston or plunger 6 adapted to be reciprocated by a gear rack 7 and pinion 8, and a crank handle 9. The liquid

is discharged through head 10 and a lateral discharge spout 11 having a downwardly extending nipple 12 at its outlet end. A check valve 14 within the base part of the pump permits the oil to be drawn into the pump cylinder from passage 5 and prevents a return flow to the tank. Thus in manipulating crank 9 to raise the valved piston the liquid above the same is forced out of the spout and downwardly through outlet nipple 12 into a suitable receiving vessel, providing the drain pipe D in line with the outlet is pushed to one side. Otherwise the stream of oil will pass downwardly through drain pipe D back into the tank.

Drain pipe D is offset between its opposite ends and the lower end thereof is rotatably seated within a chambered extension 15 at one side of base 2, thereby permitting the mouth portion 16 of pipe D to swing in an arc back and forth in respect to outlet nipple 12. Drain pipe D is held upright in a snug-fitting working position within chambered extension 15 by means of an annular collar 17 pinned to or otherwise fastened upon the base end of the pipe. Collar 17 fits snugly within a round recess 18 at the bottom of chambered extension 15, and is also seated upon an annular shoulder 19 having a central opening 20 which is in register with an opening 21 in the tank top 3 to permit the drainings from pipe D to pass directly into the tank. Leakage at the joint is prevented by maintaining a constant end thrust of collar 17 against the seat or shoulder 19, which end thrust is effected by a coiled compression spring 22 sleeved upon pipe D and held constantly in a compressed state by a separate bearing sleeve or collar 23. Bearing member 23 has a reduced body portion 24 adapted to fit snugly within the reduced upper end of the chamber within base extension 15, and a locking screw 26 holds the bearing collar in a fixed but removable position.

Thus in Fig. 2, the drain pipe is shown lifted bodily from chambered extension 15, and coiled spring 22 which is interposed between the two collars is shown herein in an expanded or elongated state. The opposite ends 27-28 of the spring are bent at right angles to interlock with the loose collar 23 and the fixed collar 17 or pipe D, so that the spring may exert a lateral force tending

to turn the pipe about its longitudinal axis when seated within base 2, providing loose collar 23 is secured against movement by locking screw 26. A series of openings 25 are formed radially in collar 23 to receive the screw, and the spring may be contracted more or less and the tension adjusted and fixed, dependent upon which opening 25 is selected and the degree of rotating given to the collar.

In entering collar 23 within the reduced upper end of chambered extension 15 it is necessary to depress the same before a connection can be completed, thereby compressing the spring and causing collar 17 to be pressed tightly against its seat 19. Screw 26 may then be entered into one of the openings 25 to lock the parts together while the mouth portion 16 of drain pipe D bears against outlet nipple 12 and prevents rotation of the pipe in one direction.

In Fig. 4, the mouth portion 16 of the drain pipe is shown as slotted at one side to admit the depending nipple 12, and a lug 29 opposite the side opening or slot 30, see Fig. 4, is adapted to engage nipple 12 and establish a definite stopping position for the drain pipe centrally in respect to the nipple. A convex plate or disk 31 may be tightly affixed to nipple 12 to serve as a guard or cover screen for the open end of the mouth piece 16. However, this disk may be omitted without changing or affecting the operation of the drain pipe in any degree.

What I desire to claim, is:

1. A liquid dispensing appliance, comprising a base member, having a chambered portion, a pipe rotatably seated within said chambered portion, a rotatable collar connected to said base member, and a coiled compression spring connected at one end to said pipe and at its other end to said collar to exert both an end thrust and a torsional force upon said drain pipe within said chambered portion.

2. A liquid dispensing pump having a base and a discharge spout, a drip and drain pipe rotatably seated within said base beneath said spout, a coiled compression spring, and adjustable means adapted to compress and also apply a torsional stress on said spring and thereby secure said drain

pipe in tensional sealing connection with said base.

3. A liquid dispensing pump, a base member for said pump provided with a drain passage and a sealing seat for a rotatable drip and drain pipe, a drip and drain pipe having an end sealing portion, a coiled compression spring sleeved upon and connected at one end to said pipe, and a tensioning collar connected with said spring and base adapted to compress said spring and hold said pipe in rotatable sealing connection with said seat, and a locking device arranged to secure said collar to the base member.

4. A dispensing pump and tank, comprising a base for the pump having a drain passage open to the top of said tank, a drain pipe having an annular sealing extremity rotatably seated within said passage, a coiled compression spring sleeved upon said pipe within said passage, a collar rotatably and slidably sleeved upon said pipe adapted to compress and place the coils of said spring under torsional stress, and means adapted to detachably secure said collar to said base.

5. A dispensing tank, a pump mounted upon said tank having a discharge spout, a drip and drain tube rotatably mounted in sealing connection with the base of said pump adapted to swing back and forth in respect to said spout, a coiled compression spring connected with said pipe adapted to exert an end thrust and a torsional force upon said pipe, and a collar sleeved upon said pipe and connected adjustably with said base arranged to compress and contract said coiled spring.

6. A dispensing pump having a base provided with a chambered portion, a drain passage and an end seat within said chambered portion, a drip collecting and return drain pipe having a seating collar at one end thereof engaging said seat, a coiled compression spring connected with said pipe within said chambered portion, a collar rotatably sleeved upon said pipe having radial openings, and a locking screw opposite said openings to secure said collar in fixed connection with said base and in compressible engagement with said spring.

In testimony whereof I affix my signature.
CHARLES SPAETH.
